UNITED STATES PATENT OFFICE.

FRIEDRICH CORRELL, OF BERLIN, GERMANY.

PRINTING DEVICE FOR CASH-REGISTERS OR CASH-DELIVERY APPARATUS.

1,141,693.

Specification of Letters Patent.

Patented June 1, 1915.

Application filed November 16, 1910. Serial No. 592,617.

To all whom it may concern:

Be it known that I, FRIEDRICH CORRELL, a subject of the German Emperor, and resident of Waterloo Ufer 19, Berlin, Germany, have invented new and useful Improvements 5 in Printing Devices for Cash-Registers or Cash-Delivery Apparatus, of which the following is a specification.

The well known cash registers and cash 10 delivery machines are provided with printing devices which print the amounts indicated by means of the keys, on a control strip which remains in the machine, and in case of cash registers also deliver a check 15 and in case of cash delivery apparatus, print on a money bag. The well known devices of this kind deliver however the check either only at the side of the register at which the attendant is standing, or only at the side 20 where the payor or the payee are standing, and for the printing of the money bags, in the cash delivery apparatus, in addition to the printing device for the printing strip remaining in the machine, there is also provided 25 a separate printing device arranged in such manner that it can be used either only by the cashier or by the payee.

This invention relates however to a printing 30 device by means of which it is possible to print alternately both the check and the money bag, and to deliver the checks alternately at both sides of the machine and to introduce the money bags to be printed, as may be desired, from the side nearest the 35 cashier or from the side nearest the payee.

Figure 1 shows a cash register, at one lateral wall of which is arranged the printing device A. Figs. 2-4 show different constructions of the printing device in side elevation, partly in section.

In a casing are mounted at the top the printing segments C set in the well known manner by means of toothed wheels D, from the key-board E.

45 The printing stamp F, after the setting of the printing segments C, is moved upward in a suitable guide plate H this being effected in a well known manner by rotating the crank G which projects from the 50 casing of the printing box A.

Between the guide plate H and the printing segments C is the space K into which can be introduced by means of the supply plates I arranged at the front and back wall 55 of the casing A, both by the cashier standing in front of the keys E, and by the payor

or by the payee standing at the opposite side of the register, a loose check or a money bag, from both sides, for printing between the printing segments C and the printing stamp F. Owing, therefore, to the particular arrangement of the two inlet openings I on both sides of the casing of the printing apparatus A, the latter is rendered conveniently accessible to, and capable of being 60 used by both the cashier and by the payor or by the payee. As, however, the checks are not generally printed in cut lengths which are introduced by hand, which latter operation on the contrary is always the case 65 with money bags, the apparatus is further designed also for printing checks on endless strips, three different constructions of the same being shown in Figs. 2-4.

As will be seen from Fig. 2, the paper 75 strip roll L for the checks, is mounted on a spindle O between a pair of levers N rotatable about a spindle M. About the said spindle O rotates also, on the inner side of the levers N, but on the outer side of the 80 paper strip roll L, a second, shorter pair of levers P, which carry at the top the guide rollers Q between which passes the paper band or strip R. The pair of levers N carry at their upper end guide rollers S intermittently driven by the friction or toothed 85 wheels, S¹ gearing with the friction or toothed wheels T operated by the crank G. The lever N is also provided with a quadrant U with stops U¹ and U² at each end, 90 in such manner that when the short pair of levers P are moved by the rod V, owing to the pin and slot engagement they strike, according to its direction of movement, either the stop U¹ or U² and in that way drive, 95 during their further movement, the long lever pair N.

At the beginning of the movement of the long lever pair N, the said pair also moves a locking device W against the driving 100 wheels S¹ of the guide rollers S. This device comprises two arms which at one end are provided with teeth adapted to mesh with the teeth of the corresponding wheels S¹; and at the other end are pivotally connected together and guided in the lever N, resting in a slight depression of the quadrant Q, whereby when the latter is moved the arms W are raised and their toothed ends locked with the corresponding teeth 105 of the wheels S¹.

The object of the device is to introduce

- the check strip R alternately through the supply opening X or X¹, from the side nearest the cashier or nearest the payor or the payee, into the intermediate space K between the printing segments and the printing stamp, and to eject it on the opposite side, according as it is desired to deliver the check on the side nearest the cashier or on the side nearest the payor or the payee.
- 5 10 by the suitable adjustment of the rod V, and consequently of the pairs of levers P and N. The difficult point of this device is that the paper strip R advanced for printing, must be first completely withdrawn from the intermediate space K and the supply opening X or X¹ before it can be again introduced into the other supply position.
- 15

Fig. 3 shows a similar construction, only in this construction there are provided two check strip rolls L which are mounted in a suitable rigid manner. In this construction a balance beam Y is connected by means of a rod Z to two levers b oscillating about the spindles a. The lever Y is so arranged that any one of the pins c, c¹ or c² can be engaged in the slot. According as the pin c or c¹ is connected to the balance beam Y driven by the cash register by means of the spindle d, the check strip R or R¹ is brought into the printing position and ejected at the opposite side. If, however, the two levers b (Fig. 3) are set in the central position by engaging the lever Y with the pin c², the check printing device will be thrown out of gear, and the same printing device C F will become free for printing money bags which can be introduced from both sides. In a similar manner the lever N, Fig. 2, may be set in central, inoperative position by the rod V.

The advance of the strip R or R¹ by the lever b through the openings I is effected by means of a clamping device arranged at the free end of the lever and engaging only in one direction. The said device consists of a fixed jaw b¹ and of a movable jaw b² pressed against the former by means of a spring. The latter jaw is provided with a pin b³. When the lever b is advanced, the two jaws b¹ and b² are pressed against each other by the spring and drive the strip. When however the lever arrives at the end of its advance movement, the pin b³ will strike pivoted switches or points b⁴ which, during the return movement will bring the pin b³ under a rail, and in that way will move the jaw b² away from the jaw b¹ in opposition to the resistance of the spring, and will hold it during the return movement of the lever in such manner that the paper strip will not be affected.

If, in the construction shown in Fig. 3, the levers b are set in the central position, no printing of the check can take place.

65 The check printing device remains working,

as there is no separate device for throwing it out of gear, but the movement of the checks is not large enough to bring them within reach of the figures of the printing device.

70

Fig. 4 shows another embodiment of the invention.

In this construction the check paper strip is always supplied from one side, while the printed strip is always ejected at one side, 75 according to the drawing, at the right hand side, that is to say, the side nearest the payor or of the payee. If, however, it is desired to have the check on the left hand side, where the cashier is standing, the flap f is brought by means of a lever e into the dotted position, so that the check ejected on the right hand side, will be deviated to the left by the flap f and the shoot g secured to the flap or arranged in a fixed manner, and 80 delivered through the opening h.

In this construction, when money bags are to be printed which in this case can also be supplied from both sides through I, the check paper strip is stopped by pressing on 90 the button i; the said stopping being effected by the roller k which presses the paper strip R against the driven roller S, releasing the check paper strip so that it cannot be advanced by the roller S even when the latter 95 is rotating.

Claims:

1. In a printing apparatus for cash registers, provided with oppositely disposed feed and delivery openings: suitable printing mechanism; means to retain a supply of material to be printed upon by said printing mechanism; means to present the material to said printing mechanism; and means to temporarily arrest the delivery of the said 100 material to permit the printing mechanism to print material other than the said material.

2. In a printing apparatus for cash registers, provided with oppositely disposed feed and delivery openings: suitable printing mechanism; means to retain a supply of material to be printed upon by said printing mechanism; a driving roller and a spring 110 pressed roller between which said material is adapted to pass to be presented thereby to said printing mechanism; and means to disengage said spring pressed roller from said driving roller to temporarily arrest the delivery of the said material.

115 3. In a printing apparatus for cash registers, provided with oppositely disposed feed and delivery openings and with a further delivery opening; suitable printing mechanism; means to retain a supply of material to be printed upon by said printing mechanism; means to present the material to said printing mechanism; and a pivoted flap to receive the printed material from one 125 of said oppositely disposed feed and de- 130

livery openings to convey it to the said delivery opening.

4. In a printing apparatus for cash registers, provided with oppositely disposed feed and delivery openings and with a further delivery opening: suitable printing mechanism; means to retain a supply of material to be printed upon by said printing mechanism; means to present the material to said printing mechanism; a pivoted flap to receive the printed material from one of said oppositely disposed feed and delivery openings to convey it to the said delivery opening; and means to place said pivoted flap in inoperative position.

5. In a printing apparatus for cash registers, provided with oppositely disposed feed and delivery openings: suitable printing mechanism; means to retain a supply of material to be printed upon by said printing

mechanism; a driving roller and a spring pressed roller between which said material is adapted to pass to be presented thereby to said printing mechanism; a pivoted flap to receive the printing material from one of said oppositely disposed feed and delivery openings to convey it to the said delivery opening; means to place said pivoted flap in inoperative position; and means to disengage said spring pressed roller from said driving roller to temporarily arrest the delivery of said material.

In testimony, that I claim the foregoing as my invention, I have signed my name in presence of two witnesses, this 4th day of November 1910.

FRIEDRICH CORRELL.
